PUNCTURING TOOL

William Bryce Beecher, Troy, Mich.

Application August 12, 1955, Serial No. 527,915

11 Claims. (Cl. 30—6.1)

This invention relates to a tool for puncturing tin plate and the like and its most particular aspect concerns a tool or utensil of the indicated type which is especially adapted for puncturing metal containers as beer and condensed milk cans.

The most commonly used beer can opener consists of a simple lever suitably formed at one end to puncture the can and carrying near such end a tang designed to hook under the bead around the top of the can to fulcrum the lever. The puncture is achieved by pulling up on the fulcrumed lever so that the puncturing portion thereof is forced downwardly through the metal. With the opening made as described, it is necessary, in order that the beer will pour freely, to repeat the operation to form a second opening, serving as an air vent. The resulting holes or cuts are of triangular shape, the apex of the triangle pointing away from the rim toward the center of the can top.

The prior opener, although inexpensive to the point that it may be given away as a premium, has a number of faults. In the first place, an undue amount of force is required to make the cut and unless the can is grasped very firmly it is prone to slip, with spilling and foaming over of a portion of the contents. Moreover, the triangular cut produced by this tool is not properly related to the top of the can. Thus, if the apex of the triangle pointed toward the rim of the can rather than toward the axis thereof a pouring spout would be provided.

My invention has as a principal object to provide an opener requiring substantially less force in use and which answers to the desideratum just mentioned.

Another object is to provide such an opener which is adapted to the opening of metal containers, as condensed milk cans, which are manufactured without beads at the ends.

Still another object is to provide an opener in the use of which the required force is applied downwardly rather than upwardly as heretofore.

Although my opener is relatively involved as compared to the prior opener, and hence is somewhat more expensive to manufacture, the additional cost is not excessive; indeed is negligible when measured in terms of the convenience the opener affords.

I shall particularly describe my invention in terms of the embodiments thereof illustrated by the accompanying drawings in which:

Figure 1 shows the form of beer can opener I presently prefer, the same appearing in side elevation applied to a can;

Figure 2 is a plan view of the opener of Figure 1, the same again being shown as applied to a beer can;

Figure 3 illustrates the principle of operation of the opener;

Figure 4 shows in side elevation the presently preferred condensed milk can opener;

Figure 5 is a plan of the last mentioned opener; and

Figure 6 is a section on the line indicated in Figure 2.

2

Referring first to Figures 1 and 2, the numeral 10 denotes a base member, which in the case of the particular embodiment, is formed on a half-circle properly dimensioned with relation to the top of the can 15. Member 10 is most suitably manufactured by a stamping and forming operation providing strengthening ridges 12 and a bead gripping snap edge 14. Also, incident to such operation there are provided two pairs of standards or supports, 16, 18 for pins, 20, 22 respectively.

10 Pins 20 extend through flanges 25 (Figure 6) carried by a puncturing element 24, which otherwise may be formed in the manner of the cutting portion of the conventional opener. The underside of element 24 is shown as engaged by the upturned portion 26 (Figure 3) of a lever member 28 having flanges 27 through which pin 22 extends. Lever 28 will be noted as having strengthening ridges and as punched out at 31 (Figure 2) to provide an air vent spike 30.

The operation of the described opener is believed obvious from Figure 3 taken in conjunction with Figure 1. Suffice it to say, that when lever member 28 is depressed puncturing element 24 is rotated on its pivot to make the triangular puncture, the completion of this puncture being marked by the formation of the air vent opening, this being the function of spike 30. The parts are restored to their relative positions shown in Figure 1, incident to application of the tool to the next can to be opened.

In the modification illustrated by Figures 4 and 5, 30 wherein like numerals denote like parts in the other figures, these numerals, however, being primed, base member 10 is formed on a full circle and has secured thereto by means of a clamping ring 34 a sleeve 36 extending downwardly of the beadless can for a distance 35 substantially as illustrated. This sleeve, which is grasped by the free hand during the opening operation, may be formed, with advantage, of natural or synthetic rubber compounded to a stiffness such that it will not tend to unduly fold or buckle thereby to complicate application 40 of the tool to the can.

It should be apparent that my invention answers fully to the stated objects thereof; also that it is subject to substantial modification without departure from the basic concept.

45 What I claim is:

1. In a can opener, the combination of a base member adapted to engage the top of the can and a pair of levers independently pivotally supported by said base member, one of said levers being formed as a puncturing element, the other being of substantially greater length and being positioned to engage the undersurface of said first lever so that when subjected to a downwardly applied force it operates to rotate said first lever thereby to make the puncture.

50 2. An opener according to claim 1 where said longer lever carries a spike serving to produce an air vent in the can.

3. An opener according to claim 1 in which said puncturing lever is formed to produce a triangular cut with 55 the apex of the triangle pointing toward the rim of the can.

4. In a can opener, the combination of an arcuate base member having a bead gripping snap edge for engagement of the top of the can, and a pair of levers independently 60 pivotally supported by said base member, one of said levers being formed as a puncturing element, the other being of substantially greater length and being positioned to engage the undersurface of said first lever so that when subjected to a downwardly applied force it operates to 65 rotate said first lever thereby to make the puncture.

5. In a can opener, the combination of an arcuate base member carrying a sleeve whereby the opener may be

maintained in proper relation to the top of the can during the opening operation, and a pair of levers independently pivotally supported by said base member, one of said levers being formed as a puncturing element, the other being of substantially greater length and being positioned to engage the undersurface of said first lever so that when subjected to a downwardly applied force it operates to rotate said first lever thereby to make the puncture.

6. An opener according to claim 5 in which said sleeve is formed of rubber compounded to a stiffness such that it will not tend to unduly fold or buckle incident to application of the opener to the can.

7. In a can opener the combination of a base member adapted to engage the top of the can and a pair of co-acting levers carried by said base member, one of said levers being formed as a puncturing element and being pivotally supported by said base member through a pair of standards integral therewith, the other of said levers being of substantially greater length and being similarly supported by said base member through a pair of standards spaced inwardly of the rim of the can from said first pair of standards, said last mentioned lever being adapted in operation of the opener to engage the undersurface of said puncturing lever so that when subjected to a downwardly applied force it serves to rotate said puncturing lever thereby to make the opening.

8. An opener according to claim 7 further characterized in that each of said levers carries a pair of apertured flanges accommodating a pin which also extends through the corresponding standards carried by said base member.

9. In a puncturing tool, a base member adapted to

engage the object to be punctured, a puncturing element pivotally supported by said base member, and means similarly supported by said base member rotatable to bring about puncturing movement of said puncturing element through surface engagement therewith.

10. In a can opener, a base member adapted to engage the top of the can, a first lever pivotally supported by said base member, said lever having a portion formed to produce a puncture, and a second lever independently pivotally supported by said base member, said second lever being swingable about its pivot to cause puncturing movement of said first lever through surface engagement therewith.

11. In a can opener, a base member adapted to engage the top of the can, a first lever pivotally supported by said base member, said lever having a portion formed to produce a puncture, and a second lever similarly supported by said base member, said second lever carrying a puncturing element and being rotatable to bring about puncturing movement of said first lever through surface engagement therewith, the completion of such movement being marked by puncturing action of the puncturing element carried by said second lever.
